UNITED STATES PATENT OFFICE.

WILLIAM F. COOPER, OF NORWALK, OHIO, ASSIGNOR TO THE A. B. CHASE COMPANY, OF NORWALK, OHIO, A CORPORATION OF OHIO.

MECHANICAL PLAYING APPARATUS.

No. 897,820.

Specification of Letters Patent.

Patented Sept. 1, 1908.

Application filed September 4, 1906. Serial No. 333,217.

To all whom it may concern:

Be it known that I, WILLIAM F. COOPER, a citizen of the United States of America, residing at Norwalk, in the county of Huron and State of Ohio, have invented certain new and useful Improvements in Mechanical Playing Apparatus, of which the following is a specification, reference being had therein to the accompanying drawing.

10 This invention relates to certain new and useful improvements in mechanical musical instruments or apparatus, and relates more specifically to that type of mechanical musical apparatus generally known as "interior players", which is that type of mechanical playing apparatus in which the player mechanism such as the pneumatics, pneumatic motor, controller-box, expression controller, etc., is arranged within the case of the piano 15 or other musical instrument to which the playing-attachment is attached.

20 My present invention relates to improvements in the mounting of the player mechanism including the bellows, pneumatics and similar appurtenant parts within the case of the piano or other keyed-instrument to which the playing attachment is attached, in such manner as to permit the ready removal of said player-mechanism from the case of the 25 musical-instrument without requiring disconnection of, or interfering in any manner with any of the parts of the piano-action, or other musical-instrument-action, or necessitating the removal of the player key-frame 30 of the player-mechanism.

35 More specifically stated, the present invention has relation to improvements in the manner in which the fingers (which will be herein termed the pneumatic-fingers) that are carried by the pneumatics of the player-mechanism, are detachably-engaged with the finger-wires of the player key-frame of the player-mechanism, and the manner in which said finger wires are actuated so as to operate 40 on the abstracts of the piano-action.

45 The present invention also relates to improvements in interior players of that type which have a tracker-box located outside the case of the instrument and adapted to be 50 swung out in front of the key-board thereof into playing-position, and the invention has for one of its objects to provide in connection with this type of device, novel means for automatically locking the keys of the musical 55 instrument as the tracker-box is moved into

playing position, so as to hold said instrument keys against vibration during the operation of the playing-attachment, and for automatically unlocking the keys of the said instrument as the tracker-box is moved to 60 non-playing position, whereby the piano or other musical instrument is in condition to be operated manually or in the ordinary manner.

65 The present invention does not concern the specific construction of the pneumatics, pneumatic bellows, or other parts of the playing-apparatus or playing-mechanism that is arranged within the case of the piano or other musical instrument, further than 70 that the pneumatics of said mechanism carry fingers for detachably-engaging the finger-wires of the player key-frame, the details of construction of such pneumatics as are employed by me in my improved playing-apparatus, being shown and described in an application filed May 17, 1906, Serial No. 317,273. 75 Neither does the present invention relate to or concern the specific construction of the tracker-box, the details of construction of 80 which are shown and described in an application filed by me July 18, 1906, Serial No. 326,642. It is, however, to be understood that the improvements do have relation to the general manner in which the playing attachment is arranged within the case of the piano or other musical 85 instrument, as they are particularly adapted to that construction in which the player-action etc., is hinged within the case of the piano or other musical 90 instrument so as to be swung out therefrom as a whole when the lower front board of the piano is removed, as is fully shown, described and claimed in an application filed by me May 29, 1905, Serial No. 262,875. 95

Having generally stated the objects of the present invention, I will proceed to describe the same in detail, reference being had in such description to the accompanying drawings showing a practical embodiment of the 100 invention, it being understood however that I do not, in such description, limit myself to the specific construction shown and described, claiming at all times the right to avail myself of equivalents such as may be 105 covered by the scope of the appended claims.

In the drawings:—Figure 1, is a transverse vertical sectional view of a piano of the upright type, showing the piano-action of the instrument, the player key-frame of the 110

player-mechanism, the manner in which the pneumatic - fingers carried by the pneumatics of the player-mechanism engage with the finger-wires of the player key-frame, the 5 manner in which the player-keys of the player key-frame engage the abstracts of the piano-action, and further showing somewhat conventionally a tracker - box swung out to 10 playing position and the manner in which the keys of the instrument are locked against movement when the tracker-box is in playing position. Fig. 2, is a view of my improved player key-frame in rear elevation, partly broken away, showing the blocks carried by 15 the finger-wires for engagement by the pneumatic-fingers carried by the pneumatics of the player-action. Fig. 3, is a longitudinal sectional view of a part of a piano key-bed, illustrating the automatically-operated locking-bar. Fig. 4, is a longitudinal sectional view of a part of the piano key-bed, showing a modified form of construction for the key locking device, the tracker-box being shown in full lines in its non-playing position, and 20 in dotted lines in its playing position. Fig. 5, is an enlarged cross sectional view of the upper bar of the player key-frame, showing more clearly how the player keys are mounted on said bar.

30 As automatic and combination pianos are well known, there is no need of describing the various parts except in so far as they may have relation to the present improvements. Therefore, in the description, in using the 35 term "piano-action" it is intended to include the group of operating parts above the manual keys for producing the stroke upon the strings, effecting recoil of the hammers, damping the strings, etc. Similarly, by the 40 term player-mechanism, it is intended to include generally, the various pneumatics that are arranged within the case of the piano beneath the key-bed and back of the lower front board of such piano case. Also, the 45 term "player key-frame" as used herein, is a generic term employed for designating generally the frame which is permanently secured in the piano case, but belongs to the player-mechanism, and includes the finger- 50 wires with the blocks thereon which are engaged by the pneumatic fingers, and the player-keys to which said finger-wires are connected, and which player-keys engage underneath the abstracts of the piano-action 55 to actuate the latter when the pneumatics collapse and the pneumatic fingers pull down on the finger-wires.

The numeral 1, indicates generally, the piano-action, and 2, one of the abstracts 60 thereof; these abstracts rest at their lower ends in the usual manner on the ordinary capstan-screws 3 carried by the piano-keys 4, and are adapted to be engaged from underneath for actuation by the player-keys 5 65 pivotally-supported on the "player key-

frame". The player key-frame comprises two bars 6 and 7, which extend horizontally within the piano case, and are securely fastened therein by screws or in any other desirable manner, and are connected adjacent 70 their ends by vertical cross-bars 6'. The upper bar 6 is shown in the present illustration, which is a preferable construction, as seated upon and secured, as by screws 8, to the upper back edge of the key-bottom 9, and just 75 back of the piano key-frame 10. Pivotaly-mounted on this bar 6 in standards or butts 11, are the player-keys 5, the standards or butts being bifurcated at their upper ends to receive the player-keys. The finger-wires 12 80 are carried by the bars 6 and 7, and have vertical movement in both of said bars.

The present construction which is an entirely practical one, shows the upper bar 6 as provided with a rearwardly-extending longitudinal flange 14, notched to receive each of the finger-wires 12, while the lower bar 7 is also provided with a horizontal flange 15, that is notched to receive the finger-wires 12, and is also provided with a longitudinal row 90 of openings 16, one opposite each notch in the flange 15 for each finger-wire; at their lower ends, the finger-wires 12 are each bent upwardly into openings 16, as clearly seen in Fig. 1, and are thus held against lateral 95 movement or displacement, while moving vertically in the notched-flanges 14 and 15 of the bars 6 and 7 respectively. This construction may be modified readily without departing from the scope of the invention. 100

Each one of the player-fingers is bifurcated in its rear end, and in this bifurcated end is pivotally-mounted a block 18, the pivot point of the block being to one side of the center, and the block being centrally- 105 apertured to receive the upper end of the finger-wire 12. The upper ends of these finger-wires 12 are screw-threaded as clearly seen in Fig. 5, these screw-threaded ends passing through the apertured blocks 18, and 110 having adjusting or regulating-nuts 19 on their upper ends.

Located on each finger-wire between the flange 14 of the bar 6 and the block 18, is a stop or buffer for engagement with the flange 115 14, and which in practice is usually a leather nut on the threaded-portion of the finger-wire and a felt washer below the nut. On each finger-wire 12 is a block 21, preferably 120 adjustably-secured thereon by a set-screw 22, so that it may be perfectly positioned and securely held on the finger-wire. These blocks are arranged alternately, as will be observed by reference to Fig. 2 of the drawings, at points approximately midway the 125 length of the finger-wires, and near the lower ends of said wires, the upper row of blocks being engaged by the fingers of one set of pneumatics of the player-mechanism, and the lower row of blocks being engaged by the 130

pneumatic-fingers of the other set of pneumatics of the pneumatic action of the player-mechanism.

The inner or forward ends of the player-keys 5 lie directly underneath and engage with the lower ends of the several abstracts 2 of the piano-action 1, the weight of the finger wires being prevented from normally acting on the player-keys so as to cause them to lift 10 or press against the abstracts, by springs 23 carried by the bar 6 back of the standards or butts 11, said springs exerting their tension against the player-keys 5 to normally hold the rear ends of the same elevated, and consequently, normally holding the finger-wires elevated.

In order that the player-keys may be supported and held against the action of the springs 23 when the player-mechanism is 20 swung out of the piano case, I provide a back-stop 8' carried by the top bar 6. This back-stop is positioned back of and below the inner ends of the player-keys 5 and serve to limit the movement of the player keys the 25 springs thus being prevented from acting against the keys 5 so as to elevate wires 12, these wires being thereby retained in such position as to insure the pneumatic fingers being positioned directly over the blocks 21 30 when the player-mechanism is swung back into position within the piano-case.

As shown in my application Serial No. 317,273 heretofore referred to, the pneumatic action of the playing attachment embodies two rows of power pneumatics, one 35 row being arranged above the other row, and the pneumatics of one row being staggered with relation to the pneumatics of the other row. This pneumatic action I have only 40 shown conventionally in the present application, being designated 24 in Fig. 1, the numeral 25 designating the power pneumatics of the upper row, and the numeral 26 designating the power pneumatics of the lower 45 row. The power pneumatics 25 of the upper row of said pneumatics each carry a finger 27 which I term the pneumatic-finger, and hence will herein use that term throughout the description and claims. Similarly, each 50 power pneumatic 26 of the lower row carries a pneumatic finger 27, the fingers 27 of the upper row 25 of power pneumatics resting upon and engaging the upper row of blocks 21 on the finger-wires 12, and the pneumatic-fingers 27 of the lower row of power pneumatics 26 resting upon and engaging the lower row of blocks carried by the finger-wires 12. It is to be understood that the 55 pneumatic-action 25 is connected by flexible tubes to the tracker board (not shown) of the tracker-box 28. It is to be observed that the pneumatic fingers 27 are not connected or fastened in any manner to the blocks 21 on the finger-wires 12, but simply lie over the 60 upper face or top of these blocks. When, 65

however, power pneumatics 25 and 26 collapse, the movement imparted to the fingers 27, by the collapsing of said power pneumatics causes them to bear down on the blocks 21, and consequently pull down on the finger-wires 12, and the rear or elevated ends of the player-keys 5, thereby throwing the forward ends of said player-keys up against the lower ends of the abstracts and forcing the hammers of the piano-action against the 70 strings of the piano to sound the note. 75

With respect to so much of the present invention as has now been described in detail, I desire to call particular attention to certain features thereof, and the advantages resultant from this construction. With the construction described, it is to be observed that the blocks 21 lie in the path of the finger 27 during the collapsing movement of the pneumatic, the relative position of the finger and its block 21 when in normal position, being such that the finger may be freely moved into and out of the plane of the path of movement of the block, this being required by reason of the lateral movement of the fingers 85 when that part of the construction of the piano player carrying the pneumatics is moved from its normal position, as a unitary structure, to separate the parts, or when being moved in the opposite direction to place 90 the several fingers 27 in proper position over their respective blocks 21. Such movements of the pneumatic-carrier can only take place without liability of breakage of parts, where the fingers and their blocks lie in parallel adjacent planes, to avoid liability of opposing edges of the fingers and blocks coming into edgewise contact when the pneumatic carrier is being moved to its normal position. 100 The position of the blocks 21 is fixed by reason of the contact of the player key 5 with back stop 8'. Therefore, the movement of the finger wires 12 during the reinflating of the pneumatics is limited by the contact of the player key with the back stop. And 105 since the positions of the fingers 27 relative to the blocks 21 must be such as to prevent the edgewise contact heretofore referred to, it will be obvious that there is required a 110 change in the pressure of contact of the finger on the block, in order that the movement of the fingers when the pneumatic carrier is being removed or replaced may be freely made. 115

I also desire to call particular attention to the construction and location of the player-keys 5 as described. By reference to Fig. 1 of the drawings, it will be observed that these player-keys are located back of and under the piano abstracts and may be readily made to operate on the abstract when located at a 120 higher level than the bottom of the abstract, or may be adjusted to engage the abstract at any desired point.

With the arrangement and construction of the player key-frame as shown and de- 130

scribed, it will be observed that when it is desired to remove the player-mechanism, comprising the pneumatics etc., which player-mechanism is in practice adapted to be swung out from the piano case, in accordance with the showing in my application Serial No. 262,875 heretofore referred to, the pneumatic fingers 27 being unconnected to the blocks 21 or finger-wires 12, move away from the said blocks or wires without disturbing the player key-frame in any manner, and, when the player-mechanism is swung back within the piano case the fingers 27 are again positioned over the blocks 21, rendering the apparatus ready for use.

I will now describe the other improvement embodied in the present application, as applied to interior playing apparatus of the type stated. This improvement comprises the automatic lock for the piano keys when the tracker-box is swung up into its playing position.

As stated, the tracker-box forming one of the elements or appurtenant parts of a complete playing attachment is generally of that type shown and described in my application filed July 18, 1906, Serial No. 326,642, in which a frame is attached to horizontally-extending supports carried by the playing-attachment. To the said frame carried by said supports, as shown and claimed in detail in said application above referred to, there is pivotally-secured a tracker-box carrying-frame 29. In my present improvement, I utilize this frame in effecting the automatic locking of the piano-keys, making the said frame in one form of construction shown, the actuating-member or element for moving the locking bar into locking position when the tracker-box is swung out to playing position. In another embodiment of the invention shown, I utilize the tracker-box frame when the tracker-box is in the non-playing position as the element for holding the locking-bar in the lowered or unlocked position. This improvement embodies broadly, therefore, means for positively and automatically locking the keys of the piano or other instrument against vibration when the player-mechanism is being used, and means for automatically releasing the lock for said keys when the tracker-box of the player-mechanism is moved to non-playing position.

In the construction shown in Figs., 1 and 3, the principle involved is one in which the tracker-box carrying frame 29 is employed as the acting element for moving the key-locking bar into locking-position when the tracker-box is moved to playing position, while in Fig. 4, the principle of construction involved, while accomplishing exactly the same results, is one in which the key-locking bar is held in the unlocked position by the carrying-frame of the tracker-box when the latter is in the closed or non-playing position.

Referring first to the construction shown in Figs., 1 and 3, the locking-bar 30, is arranged beneath the piano-keys 4 near the forward ends of said keys, and above the key-frame 10. In practice, this locking-bar is provided on its upper face with a facing or strip of felt or the like to engage with the piano-keys 4. The bar is hinged at one or more points as shown at 31, to the key-frame 10, and is held down positively by one or more springs 32. In the key-frame and key-bed, is mounted for vertical-movement a plunger or pin 33, projecting normally a slight distance below the bottom of the key-bed. When the tracker-box 28 is swung or moved out to its playing position, as shown in Fig. 1, the plunger or pin 33, is engaged by a stud or pin 34 carried by the tracker-box carrying-frame 29, and the pin or plunger 33 is forced upwardly so as to elevate the locking-bar 30, raising same against the underneath face of the piano-keys 4, thus locking the said keys and holding them against vibration as long as the playing-attachment is being used. When, however, the tracker-box is swung back underneath the key-bed to non-playing position, the pressure on pin or plunger 33 is relieved, and the spring or springs 32 force the locking-bar 30 down flat against the key-frame 10, and the keys 4 are free to be played by hand.

In the construction involved in the showing in Fig. 4, the locking-bar 30 is arranged in the same position, but the springs 32 are disposed or arranged to act against the bar to normally elevate the same. Extending from the bar downwardly and rearwardly through a slot in the key-bed is an arm 35, which terminates below the key-bed at a point where it will be engaged by the tracker-box carrying frame as the tracker-box is moved to the closed or non-playing position, and the rear or free end of the arm forced upwardly, causing the arm to pull down on the locking-bar 30, and hold the same in its lowered or unlocked position as long as the tracker-box is left in the closed or non-playing position. As soon, however, as the tracker-box is swung out to playing position, the spring or springs 32 act against the locking bar 30, to move it into locking position, immediately upon the tracker-box carrying-frame moving out of engagement with the rear or free end of the arm 35. In both constructions, it will be observed the piano-keys are positively locked or held against vibration or depression while the playing apparatus is being operated, though when the tracker-box is moved to non-playing position, the keys 4 of the piano are free to be manually operated.

Having fully described my invention, what I claim is:—

1. In an automatic playing piano, the combination with the piano action including abstracts, of abstract actuating devices corre-

sponding in number to the abstracts, and means for independently actuating said devices, said means having a disengageable make and break engagement with the actuating devices, the normal position of the abstract actuating-devices relatively to the action remaining unaffected by the disengagement therefrom of said means.

5. In an automatic playing piano, the combination with a piano, movable player-mechanism, including power pneumatics arranged within the case of the piano, and a piano-action including abstracts, of a player key-frame secured within the piano case and embodying pivoted player-keys, one for each abstract and adapted to engage said abstracts to actuate the same, said player key-frame also embodying vertically-movable finger-wires, one for each player key and connected thereto, and a make-and-break engagement between each of said finger-wires and the power pneumatics of said pneumatic-action.

3. In an automatic playing piano, the combination with the piano action including abstracts, of abstract actuating devices corresponding in number to the abstracts, and means extending into the plane of the path of movement of the devices for independently actuating them, said means having a disengageable make and break engagement with the actuating devices as a unitary structure, the normal position of the abstract actuating-devices relatively to the action remaining unaffected by the disengagement therefrom of said means.

4. In an automatic playing piano, the combination with a piano-action including abstracts, of a movable interior playing mechanism including power pneumatics, a permanently-mounted key-frame including pivotally-mounted player-keys, one for each abstract and engaging said abstracts to actuate the same, finger-wires carried by said player key-frame, one for each player-key and connected at their upper ends to said player-keys, a block carried by each finger-wire, and a pneumatic finger carried by each power pneumatic of said player-mechanism, the said blocks and the said pneumatic fingers constituting a note-sounding, make and break engagement between each power pneumatic and its corresponding abstract.

5. In an automatic piano player, the combination with a pneumatic playing mechan-

ism including power pneumatics, and the piano-action including abstracts, of player-keys, one for each abstract positioned back of and engaging under the abstracts, and operating connections between the power pneumatics of said playing-mechanism and the player-keys and operating on said player-keys to actuate the abstracts.

6. In an automatic piano player, the combination with a pneumatic playing mechanism including power pneumatics, and the piano-action including abstracts, of player-keys, one for each abstract, positioned back of and engaging under the abstracts, and detachable make-and-break connections between the power pneumatics of said playing-mechanism and the player-keys.

7. In an automatic piano player, the combination with the abstracts, of a plurality of independently-actuated power pneumatics, each having an operating finger, and a corresponding number of abstract-actuating devices located in the path of movement of said fingers and engageable therewith, the relative arrangement of the fingers and devices providing a make and break contact therewith, the pneumatics and their operating fingers being movable out of the plane of the path of movement of the abstract actuating devices as a unitary structure, the normal position of the abstract actuating-devices relatively to the abstracts remaining unaffected by the disengaging movement of the pneumatics and their operating fingers.

8. In an automatic piano player, the combination with the abstracts, of a plurality of independently-actuated power pneumatics, each having an operating finger, and a corresponding number of abstract actuating devices permanently located in the operable path of movement of said fingers, the movement of each finger being of a length relative to the length of movement of the abstract actuating devices such as to permit the finger to be freely moved laterally out of the plane of the path of movement of said devices without affecting the normal position of said devices relatively to the abstracts.

In testimony whereof I affix my signature in the presence of two witnesses.

WILLIAM F. COOPER.
